SPINDLE BAR MOUNTING BRACKET
AND THE LIKEBuford W. Olson, Minneapolis, Minn., assignor to
Chas. Olson & Sons, Inc., Minneapolis, Minn., a
corporation of Minnesota

Application December 2, 1949, Serial No. 130,642

7 Claims. (Cl. 280—1)

1

My invention relates to means for mounting spindle bars and the like on utility trucks for use in laying electrical cable and like operations.

In the laying of some types of electrical cables, particularly in underground installations, a spool of said cable is mounted in a truck body and dispensed therefrom at the point of installation. To facilitate the dispensing of the cable, it is desired to feed the same from the mounted spool over an idler pulley mounted for rotation and free axial sliding movements on a spindle bar extending transversely of the truck above the rear end of the body platform, preferably near the top of the truck. When the vehicle is used for other purposes, it often becomes necessary to remove the pulley and spindle bar so that they do not hinder loading and unloading of the truck with other equipment. Therefore, an important object of my invention is the provision of bracket means for supporting a spindle bar and pulley as set forth, wherein said spindle bar may be quickly and easily installed and removed.

Another object of my invention is the provision of means for positively locking said spindle bar in its operative position.

Another object of my invention is the provision of brackets as set forth having means thereon for locking in their operative positions canopy anchoring rods extending longitudinally of the truck body at opposite sides thereof.

Another object of my invention is the provision of bracket means as set forth, which are inexpensive to manufacture and install, efficient in operation, rugged in construction, and durable in use.

Other highly important objects and advantages of my invention will become apparent from the following detailed specification, appended claims, and attached drawings.

Referring to the drawings, wherein like characters indicate like parts throughout the several views:

Fig. 1 is a view in side elevation of a utility truck having my novel supporting brackets attached thereto, some parts being broken away;

Fig. 2 is an enlarged fragmentary view in end elevation as seen from the line 2—2 of Fig. 1;

Fig. 3 is a still further enlarged fragmentary view, partly in section and partly in side elevation, taken substantially on the line 3—3 of Fig. 2;

Fig. 4 is an enlarged fragmentary detail as seen from the line 4—4 of Fig. 2, some parts being broken away and some parts being shown in section; and

2

Fig. 5 is an axial section, taken substantially on the line 5—5 of Fig. 4.

Referring with greater particularity to the drawings, the numeral 1 indicates in its entirety 5 the conventional utility truck of the type used in electrical service work, such as laying electrical cable, repairing power lines and equipment, etc. The truck 1 includes front and rear wheels 2 and 3, respectively, a cab 4, and a body portion 5 comprising the usual rectangular platform 6 and rigid side frame or wall members 7 and 8.

A spool 9 is illustrated as being journaled in suitable bearing brackets 10, one of which is shown, and carries a length of electrical cable 11 or the like 11. The cable 11, when being installed, is dispensed from the spool 9 over an idler pulley 12 journaled for rotation and free for axial sliding movements on a spindle bar 13 extending transversely of the truck body 1 at the rear end 10 thereof. The spindle bar 13 is loosely secured in a pair of socket forming brackets 14 and 15, the former of which is rigidly secured to the upper rear corner portion of the side frame member 7, and the latter to the upper rear corner portion 20 of the side frame member 8, by bolts or the like 16.

The brackets 14 and 15 are respectively provided with opposed sockets 17 and 18, which are adapted to contain opposite end portions of the spindle bar 13. A plate or bar 19, welded or 30 otherwise rigidly secured across the top of the bracket 14 forms one wall of the socket 17 and permits movements of the engaged end of the spindle bar with respect thereto, only in a direction substantially axially of the spindle bar 13. 35 The socket 18 of the bracket 15 opens both horizontally toward the opposed socket 17 and upwardly, whereby to permit upward movement of the end portion of the spindle contained therein, radially of the axis thereof. Such upward movement of the last-named end of the spindle bar 13 40 out of the socket 18 permits the opposite end thereof to be drawn axially outwardly of the socket 17.

The end of the spindle bar 13 supported in the 45 socket 18 is provided with an axially-outwardly opening recess 20, which is in axial alignment with a restricted opening 21 in an end wall 22 of the bracket 15 when the spindle bar 13 is supported in the socket 18. The restricted opening 50 21 extends through the end wall 22 and forms the interior of a sleeve 23 integrally formed with the bracket 15. A lock pin 24 is mounted for axial sliding movements in the opening 21, the inner end thereof being extensible and retractable into and out of the recess 20 in the spindle

bar (see Figs. 4 and 5). A handle-equipped finger 25 is rigidly secured to the intermediate portion of the lock pin 24 and projects radially outwardly therefrom through a bayonet slot 26 in the sleeve 23. As shown, when the lock pin 24 is rotated on its own axis and moved axially from its recess-engaging position, illustrated by full lines in Fig. 5, to its retracted position, shown by dotted lines in Fig. 5, the adjacent end of the spindle bar 13 may be moved radially upwardly out of the socket 18, after which the spindle bar may be drawn axially out of the socket 17 for disposal in a convenient location on the truck. This arrangement provides unrestricted access to the rear of the truck body and permits loading and unloading of other equipment without interference. Remounting of the pulley-equipped spindle bar 13 is quickly and easily accomplished by moving the same axially into seating engagement of one of its ends with the socket 17, and dropping the other end radially into the socket 18, after which the lock pin 24 is moved to its full-line position of Fig. 5, the inner end thereof being extended into the recess 20 of the spindle bar. The lock pin 26 in the bracket 15 and the plate 19 on the bracket 14 prevents accidental removal of the spindle bar 13 from the sockets 18 and 17 thereof.

A protective canopy-like cover 27, preferably of canvas or the like, is arranged to overlie a truck body and is supported by a plurality of arched ribs 28 which extend transversely of the truck body 5 and have their opposite ends rigidly but detachably secured to the opposite side frame elements 7 and 8 in a suitable manner. As shown, the canopy 27 is stretched over the ribs 28 and at its opposite side edges is formed to provide longitudinally-extending loops 29 through each of which extends an anchoring rod 30. Said anchoring rods 30 have their front ends longitudinally slidably receivable, one each in each of a pair of laterally-spaced brackets 31, one of which is shown, rigidly mounted on the side frame sections 7 and 8 adjacent the cab 4 of the truck. The rods 30 may be tubular or solid, but, in any event, are provided at their rear ends with axially outwardly opening recesses, which are adapted to receive lock pins 32. The lock pins 32 are each mounted for rotary and free axial sliding movements in aligned apertures through pairs of spaced ears 33, one pair projecting laterally outwardly of each bracket 14 and 15 and formed integrally therewith. Opposite pairs of ears 33 are connected by integrally-formed reinforcing ribs or the like 34, which are notched adjacent the forward ears, as indicated at 35 to receive one of a pair of handle-equipped fingers 36 that project radially outwardly, one each from each of the lock pins 32 between the ears 33. The lock pins 32 operate to secure the rear ends of the anchoring rods 30 in the same manner as the lock pin 24 secures its cooperating end of the spindle bar 13. When the lock pins 32 are projected forwardly so that their front end portions engage the recesses in the rear ends of the anchoring rods 30, the fingers 36 are registerable with the notches 35. Rotary movement manually imparted to the lock pins 32 causes the fingers 36 to be received within said notches, whereby to prevent axial movement of the lock pins 32 in a direction to become disengaged from the anchoring rods 30.

The novel construction and arrangement of parts above described has been found to be completely satisfactory for the accomplishment of

the objectives set forth; and while I have shown and described a preferred embodiment of my invention, it should be understood that the same is capable of modification without departure from the spirit and scope of the invention, as defined in the claims.

What I claim is:

1. In combination with a truck body having a generally rectangular platform and laterally-spaced rigid side frame members and cable spool mounting means on said platform, a pair of co-operating socket-forming brackets secured to the rear end of said side frame members in opposed relationship, one of said sockets opening horizontally and the other thereof opening horizontally and upwardly, a spindle bar seated in said opposed sockets and displaceable axially with respect to one of said sockets and radially upwardly with respect to the other, an axially opening recess in the end of said spindle bar end seated in the upwardly opening socket, a restricted opening in the end wall of said last named socket axially aligned with the recess in said spindle bar, and an extensible and retractable lock pin mounted for sliding movements in the restricted opening of said bracket for movements into and out of said recess.

2. The structure defined in claim 1 in which the bracket having the upwardly opening socket therein is provided with a guide sleeve for said lock pin, said guide sleeve being provided with a bayonet slot and said lock pin having a finger projecting radially outwardly therefrom through said bayonet slot.

3. The structure defined in claim 1 in which each of said brackets is provided with spaced bearing lugs which project in opposite directions longitudinally of said spindle bar, said bearing lugs being vertically spaced with respect to said restricted opening and lock pin, each pair of bearing lugs having openings on aligned horizontal axes, and in further combination with a pair of laterally-spaced brackets at the front end of said truck body, each of said last-mentioned brackets having a rearwardly-opening socket in axial alignment with one of the said pairs of openings in said bearing lugs, a pair of canopy anchoring rods having their front ends receivable one each in one of said sockets, the rear ends of said rods having axially outwardly-opening recesses therein, and a pair of lock pins slidably mounted one each in each pair of aligned openings in said bearing lugs, the front ends of said lock pins each being movable into and out of the recess in an adjacent anchoring rod.

4. In combination with a truck body having a generally rectangular platform, laterally-spaced rigid side frame members, a displaceable canopy-like top, and cable spool-mounted means on said platform, a pair of co-operating socket-forming brackets secured to the rear end of said side frame members in opposed relation, one of said sockets opening horizontally and the other thereof opening horizontally and upwardly, a spindle bar seated in said opposed sockets and displaceable axially with respect to one of said sockets and radially upwardly with respect to the other, an axially-opening recess in the end of said spindle bar seated in the upwardly-opening sprocket, a restricted opening in the bracket end wall of said last-named socket axially aligned with the recess in said spindle bar, an extensible and retractable lock pin mounted for sliding movements in the restricted opening of said

bracket for movements into and out of said recess, a pair of spaced bearing lugs on each of said brackets, each pair of said lugs projecting in opposite directions longitudinally of said spindle bar, each pair of said lugs further having aligned openings therethrough on horizontal axes, a pair of laterally-spaced brackets at the front end of said truck body, one each of said last-named brackets operatively associated with one of the brackets at the rear end of said side frame members, a pair of canopy anchoring rods having their front ends removably secured to said brackets at the front end of said truck body, the rear ends of said rods being provided with axially outwardly-opening recesses, and a pair of lock pins slidably mounted one each in each pair of aligned openings in said bearing lugs, the front end of each of said lock pins being axially movable into and out of the recesses in an adjacent anchoring rod.

5. The structure defined in claim 4 in which the brackets at the front end of said truck body are provided with rearwardly-opening sockets one each in axial alignment with the openings in one of said pairs of bearing lugs, the front ends of said anchoring rods being receivable one each in one of said last-named sockets.

6. The structure defined in claim 4 in which the bracket having the upwardly-opening socket therein is provided with a guide sleeve for said spindle lock pin, said guide sleeve being provided with a bayonet slot and said pin having a finger projecting outwardly therefrom through said bayonet slot.

7. The structure defined in claim 4 in further combination with fingers projecting radially from the lock pins for said anchor rods and engageable with notches in said first-named brackets whereby to prevent axial movements of said last-named lock pins in their extended anchor rod-engaging positions.

Certificate of Correction

Patent No. 2,529,738

November 14, 1950

BUFORD W. OLSON

It is hereby certified that error appears in the printed specification of the above numbered patent requiring correction as follows:

Column 3, line 26, for the word "prevents" read *prevent*; column 4, line 60, for "spool-mounted" read *spool-mounting*; line 71, for "sprocket" read *socket*; column 5, line 10, for "end" read *ends*;

and that the said Letters Patent should be read as corrected above, so that the same may conform to the record of the case in the Patent Office.

Signed and sealed this 17th day of April, A. D. 1951.
